CAMERA

Sho Shiramatsu, Osaka, and Eisuke Terada, Toyonaka,
Japan, assignors to Minolta Camera Kabushiki Kaisha,
Osaka, Japan, a corporation of Japan

Filed Oct. 28, 1964, Ser. No. 82,350

Term of patent 14 years

(Cl. D61—1)

FIG. 1

FIG. 2

FIG. 1 is a top plan view of a camera showing our new design; and

FIG. 2 is a perspective view thereof.

The essential feature of the camera design resides in the specific distance and exposure indicator as shown in full lines on the top of the camera. The rear of the camera not shown is of conventional appearance.

We claim:

The ornamental design for a camera, as shown and described.
